H. JARVIS,
THERMOSTATIC CONTROLLER FOR GAS WATER HEATERS,
APPLICATION FILED DEC. 13, 1916.

1,286,012.

Patented Nov. 26, 1918.

Inventor.

Harold Jarvis,
by H. J. Dennis, atty.

UNITED STATES PATENT OFFICE.

HAROLD JARVIS, OF TORONTO, ONTARIO, CANADA.

THERMOSTATIC CONTROLLER FOR GAS WATER-HEATERS.

1,286,012.

Specification of Letters Patent. Patented Nov. 26, 1918.

Application filed December 13, 1916. Serial No. 138,622.

To all whom it may concern:

Be it known that I, HAROLD JARVIS, a subject of the King of Great Britain, and resident of the city of Toronto, county of York, Province of Ontario, in the Dominion of Canada, have invented certain new and useful Improvements in Thermostatic Controllers for Gas Water-Heaters, as described in the following specification and illustrated 10 in the accompanying drawings, that form part of the same.

The principal objects of the invention are to improve the device shown in my previous United States Patent No. 1,172,459 in such a 15 manner as to absolutely prevent the possibility of the gas valve being opened slowly and insuring a quick snap opening of the valve and a consequent full flow of gas to the burner.

20 A further object is to provide a simple means for regulating the magnetic pull upon the armature and thereby effecting a saving in time and consequent cost in manufacture.

The principal feature of the invention 25 consists in the novel manner of opening the valve controlling the gas supply to the burner by causing it to be engaged by a thermostatically operated arm with a sharp impact at a point intermediate of the movement of said lever.

In the drawings, Figure 1 is a sectional plan view of the device to which my improvement is applied.

Fig. 2 is a central longitudinal section of 35 the device shown in Fig. 1.

Fig. 3 is a transverse vertical section of the device taken through the center of the gas outlet.

Like numerals of reference indicate 40 corresponding parts in each figure.

Referring to the drawings, the casing 1 in which the gas control mechanism is arranged is provided with a thermostat 2 which extends into the water to be heated 45 and the interior of said casing is connected to a suitable gas supply through the passage 3.

A valve seat 4 is arranged at the opening to the gas pipe 5 leading from the casing 1.

50 6 is a bracket bridged over the valve seat 4 having a central sleeve portion 7.

The valve 8 which is of part spherical shape rests upon the valve seat 4 and is provided with a stem 9 extending loosely

through said sleeve, a spiral spring 10 surrounding the stem and lower part of the sleeve, holding the valve to its seat.

The side arms of a horseshoe magnet 11 are located at the sides of the casing and extend to or beyond the ends of the 60 bracket 6.

The magnet armature 12 supported on the pivotal break joint arm 13 extends over the top of the bracket 6 and is provided with a hole 14 through which the upper end of 65 the valve stem 9 extends, said stem being loose therein and having the lock nuts 15 at the top adapted to be engaged by the armature in its upward movement to lift the valve from its seat.

70 The arm 13 is formed with a break joint 16 intermediate of its length and the section carrying the armature 12 is connected at its rear end to a spring 17 secured to the casing. The pull of the spring 17 acts 75 against the magnetic pull upon the armature and when the upward pressure of the thermostat 2 against the arm 13 is sufficient to overcome the magnetic pull the spring 17 then pulls the outer pivotal end 18 of the 80 arm 13 down with a quick snap. This action throws the armature 12 upwardly and it engages the nuts on the valve stem 9 thereby lifting the valve with a quick snappy action.

85 When the thermostat acts to lower the arm 13 the armature is pulled down with a quick snap magnet action and the valve is thus closed quickly.

In order to overcome the difficulties in adjustment owing to the varying strength of pull of magnets I provide a pair of adjusting screws 19 threaded in the ends of the armature 12. These screws are of brass and projecting below the armature they rest 90 upon the side arms of the magnet and prevent the armature sticking. The screws 19 may be adjusted as desired to increase or decrease the gap between the armature and magnet and thus regulate the action as desired. This feature obviates a lot of fitting in the manufacture of the device and effects a considerable saving in cost.

100 It will be understood that as the valve stem is loose the valve will seal itself under 105 the action of the spring 10 and if there is any tendency for one side of the armature to lag behind the other in releasing from the

magnet the valve will not be affected but will be opened only upon the snap action lifting it bodily from its seat.

Gas burners as a rule are so constructed that if the supply of gas to them is slow they will back fire on being lighted. With the present device this is positively overcome, particularly in view of the fact that in addition to the very rapid opening of the 10 valve, the valve casing contains a considerable volume of gas under pressure and this is at once released to the burner.

With my present construction the valve stem is mounted in the sleeve of the bracket 15 secured to the base. The valve stem comes up through a considerably larger hole in the magnet plate with the lock nut fastened to the stem above the magnet plate.

The valve is absolutely not disturbed until 20 the spring tension has overcome the magnetic attraction and the snap takes place giving a very strong impact against the lock nuts of the plunger valve which makes a flash opening and will light any burner that 25 can be lighted by hand.

What I claim as my invention is:—

1. In a thermostatic controller for gas

water heaters, the combination with a thermostatically operated break joint arm having an armature at its outer end and a magnet 30 adapted to attract said armature, of a bracket extending over the gas outlet arranged beneath said armature, a valve for closing the gas outlet having its stem extending through said bracket and through 35 said armature a spiral spring encircling said valve stem between the valve and bracket and holding the valve to its seat, and an adjustable stop on the valve stem above the armature adapted to be engaged by the 40 armature to raise the valve from its seat.

2. In a thermostatic controller for gas water heaters, the combination with a thermostatically operated break joint arm having an armature at its outer end and a magnet having its pole ends arranged to attract the ends 45 of said armature, of non-magnetic adjusting screws arranged in the ends of said armature adapted to engage the pole ends of the magnet, and a gas valve loosely connected 50 to said armature and adapted to close the gas supply.

HAROLD JARVIS.
